(57) **CLAIM**

We claim the ornamental design for an image scanner, as shown and described.

DESCRIPTION

FIG. 1 is a perspective view of an image scanner, embodying our new design, shown without the slide film stage;

FIG. 2 is a front view thereof;

FIG. 3 is a top plan view thereof;

FIG. 4 is a right side view thereof;

FIG. 5 is a left side view thereof;

FIG. 6 is a rear view thereof;

FIG. 7 is a bottom side view thereof;

FIG. 8 is a reference perspective view of FIG. 1 with the arm folded to be stored;

FIG. 9 is a reference perspective view of FIG. 1 with the camera head facing the front of the table;

FIG. 10 is a reference perspective view of FIG. 1 with the camera head facing the rear of the table;

FIG. 11 is a reference perspective view of FIG. 1 with the cover at the rear end of the table top open;

FIG. 12 is a reference right side view of FIG. 1 with the cover at the rear end of the table top open;

FIG. 13 is a reference rear view of FIG. 1 with the cover at the rear end of the table top open;

FIG. 14 is a reference perspective view of the image scanner of FIG. 1 shown with the slide film stage placed;

FIG. 15 is a reference front view thereof;

FIG. 16 is a reference right side view thereof;

FIG. 17 is a reference rear view thereof;

FIG. 18 is a reference top plan view thereof; and,

FIG. 19 is an enlarged reference perspective view showing the slide film stage alone.
